UNITED STATES PATENT OFFICE.

FRANK PAVLIK, JR., OF WESTMINSTER, COLORADO.

DRY CLOSET.

1,287,739.

Specification of Letters Patent. Patented Dec. 17, 1918.

Application filed April 3, 1918. Serial No. 226,434.

To all whom it may concern:

Be it known that I, FRANK PAVLIK, Jr., a citizen of the United States, residing at Westminster, in the county of Adams and 5 State of Colorado, have invented certain new and useful Improvements in Dry Closets; and I do hereby declare the following to be a full, clear, and exact description of the invention, such as will enable others 10 skilled in the art to which it appertains to make and use the same.

This invention relates to improvements in dry closets of the indoor chemical type, and especially to that class which are detachably 15 associated with an air outlet conduit for ventilating purposes, coöperating with the action of a suitable chemical or the like, preferably in liquid form, introduced into the fecal container, for relieving its contents of 20 foul odors and other unsanitary conditions.

As the general aims and advantages of this type of closets are fully understood, it will be unnecessary to further initially refer to the objects of the present improvements, 25 which will be clearly apparent as incidental to the following disclosure, although by way of emphasis it may be said that the invention is more peculiarly adapted for use on the farm, homestead, or other outlying localities, where the usual water flushing 30 closets may not be feasibly installed, owing to lack of water facilities and sewerage systems.

With these prefacing remarks, the invention 35 consists of the combination and structural arrangement of parts as hereinafter described, the essential features of novelty being more succinctly set forth in the appended claims, but to more clearly understand the invention, reference will now be had to the accompanying drawings illustrating a preferred embodiment of the same, 40 in which drawings like reference characters designate the same parts in the several 45 views, of which—

Figure 1, is an elevational view of the installed closet, the upper portion of the container receptacle being broken away and the seat therefor being shown in section; Fig. 2, 50 is a detail sectional view through the coupling connections, being taken along the plane of the line 2—2 of Fig. 1, and showing the upper portion of the base standard in

front elevation; and Fig. 3, is a detachably associated detail view of the coupling connections. 55

10 designates the closet proper, which is of a readily attachable and detachable single container type, provided with the usual bail 11, and a hand grip element 12 at its lower 60 end, for assisting in tilting the container, when removed for emptying and washing out.

13 designates a removable apertured seat, recessed around its lower peripheral face, as 65 at 14, to detachably fit the upper edge face of the container 10, and this seat is provided with the usual hinged closure lid 15.

The container, at its upper rear portion, has a foul air outlet 16, from which projects 70 an upper or topping member of a two-part coupling of a peculiar structure, which coupling forms one of the essential features of the present invention.

This upper or topping member of the 75 coupling, at the end where it leads from the foul air outlet 16, is of cylindrical formation, as at 17, and toward its projecting outer end the underneath wall thereof is cut away to provide an overlapping upwardly 80 convex tongue portion 18, the underneath edge faces of which incline downwardly, as at 19, from its forward edge face 20 to its joinder with the cylindrical portion 17, forming the upwardly concave shoulder 21. 85

The tongue portion 18 is apertured at 22, through its upper wall, and the whole element coöperates with a complementary oppositely disposed lower receiving member of the coupling, with a scarf-like joinder, the 90 receiving member being similarly shaped although in reverse disposition, and the corresponding parts of which are designated by the numerals 23, 24, 25, 26 and 27, respectively, while the top surface of the cylindrical portion thereof is provided with a projecting lug 28, preferably tapered or conical, adapted to fit within the aperture 22 of the tongue portion 18, providing centering and interlocking means therebetween. 100

These coupling members, therefore, provide concavo-convex tongue portions of overlapping trough-like formation, and the cylindrical portion 23 of the lower member terminates in an elbow arm 29, which in turn 105 telescopes with a section 30 of a vent pipe

2
leading, in any suitable manner, to the atmosphere exteriorly of the building where the closet is installed.

Another important feature of my invention resides in the structural formation of the base standard 31 and the manner of adjustably securing the lower coupling member thereto, with its vertical elbow arm 29 in telescoping alinement with the vent pipe section 30, thus compensating for any unevenness of the floor relatively to the positions of the container 10 and the base standard, and hence the proper positioning of the lower and topping coupling members, so 15 that they will fit each other snugly in readily separable and attaching relations.

The lower body of this base standard is preferably conical, being provided at its bottom with a securing flange to rigidly fix 20 the same to the floor or other support, but it is to be especially noted that its upper end 32 is of cylindrical formation and of a diameter slightly greater than that of the vertical elbow arm 29 of the lower coupling 25 member.

The lower forward wall of this cylindrical top portion 32 is cut away to provide an elongated opening or slot 33, adapted to freely receive the elbow portion of the lower 30 coupling member. From the upper end of this slot, the cylindrical portion 32 is slit or separated to its top edge face, as indicated at 34, and adjacent thereto the contiguously disposed parallel vertical ears 35, or lugs, project laterally therefrom, being adapted to be drawn together or eased up by the tightening bolts 36 or their equivalent.

In assembling the parts, the elbow section 29 of the lower coupling member is inserted upwardly through the slot 33, when 40 it may be clamped within the cylindrical portion 32, in properly adjusted position, by tightening up the bolt elements 36.

45 It will be evident that, when the container 10 is to be placed in set up position, the cylindrical portion 17 of the upper coupling member will fit snugly within the trough-like tongue portion 24 of the lower coupling member, and reversely the tongue portion 18 of the upper member will likewise fit snugly over the cylindrical portion 23 of the lower member, while the lug 28 enters the aperture 22 and the coupling elements 50 are readily interjoined and securely interlocked against lateral displacement, by simply lowering the container receptacle, with the upper coupling member registering with and fitting down over the lower 55 one.

60 As in similar types of closets, I also employ a suitable chemical mixture in the container, and the noxious odors and gases, not entirely thrown down or killed by the

chemical action, are carried away through 65 the vent pipe by way of its coupling with the container. Also, while not essential, it is obvious that any of the well known means of forced draft, sometimes used in ventilating systems generally, might be employed, 70 if desired.

With the foregoing complete disclosure, it is thought that a further detailed description of the operation would only be superfluous, and while it will be understood that 75 I do not make any broad claims to the detachable coupling up of a dry closet container to a vent pipe generally, at the same time, I do not limit myself to the exact details as set forth, excepting as come within 80 the terms of the ensuing claims, as viewed in the light of the specification, contemplating a fair range of equivalents.

What I do claim as new and patentable 85 is:

1. In ventilated dry closets, of the type wherein the usual container receptacle is provided with a foul air outlet adapted for communication with a vent pipe, the employment of coupling means, embodying a 90 separable ventilating conduit between said foul air outlet and said vent pipe, comprising a cylindrical member projecting laterally from said vent pipe, the forward end thereof being cut-away on its top to form 95 an upwardly concave receiving tongue of a lower coupling element, and a reversely disposed associated member, extending from said foul air outlet, having a cylindrical portion and an underneath cut-away forward 100 portion, providing an upwardly convex seating tongue of an upper coupling element, said members being complementally proportioned and functioning, in readily attachable and detachable relation, to provide for 105 a snug interunion therebetween, substantially as described.

2. In ventilated dry closets, the combination with the usual container having a foul air outlet adapted for communication with a vent pipe; of a base standard, adapted to be mounted in line with said vent pipe, having a hollow cylindrical head, the forward portion of said cylindrical head being cut-away to provide a lower enlarged vertical 115 slot terminating in a slit extending to the top of the head, and the whole providing a springy clamping head; an elbow extended through said head, with its vertical arm projecting upwardly therethrough, into connection with said vent pipe, and with its lateral arm projecting freely through said enlarged slot; means for tightening and loosening said clamping head around the vertical arm of said elbow; and coupling means between 120 said lateral arm, as a coupling element, and the foul air outlet of said container, substantially as described.

3. In ventilated dry closets, the combination with the usual container having a foul air outlet adapted for communication with a vent pipe; of a base standard, adapted to 5 be mounted in line with said vent pipe, having a hollow cylindrical head, the forward portion of which is cut away to provide a lower enlarged vertical slot terminating in a slit extending to the top of the head and 10 provided with contiguously disposed vertical ears; an elbow extending through said head, with its vertical arm projecting upwardly therethrough, into connection with said vent pipe, and with its lateral arm projecting 15 freely through said enlarged slot, the forward end of said lateral arm being cut-away on its top to provide an upwardly concave

receiving tongue of a lower coupling element; clamping means for said vertical ears; an upper coupling element, extending 20 from the foul air outlet of said container, having a cylindrical portion and an underneath cut-away forward portion providing an upwardly convex seating tongue; and a pin and hole interlocking connection between the tongue portion of one member 25 and the cylindrical portion of the other, said coupling elements being complementally proportioned, and the whole construction and combination functioning, substantially 30 as described.

In testimony whereof, I affix my signature.

FRANK PAVLIK, JR.
